UNITED STATES PATENT OFFICE.

SAMUEL E. DIESCHER, OF PITTSBURGH, PENNSYLVANIA, ASSIGNOR TO S. DIESCHER & SONS, OF PITTSBURGH, PENNSYLVANIA, A PARTNERSHIP CONSISTING OF SAMUEL E. DIESCHER AND AUGUST P. DIESCHER.

PIERCING MILL.

Application filed February 18, 1926. Serial No. 89,111.

The invention relates to mills for piercing billets to form hollow metal blanks for manufacturing seamless tubing by the several methods used in its production, it being understood that the term "mill" is herein used to include a stand of piercing mill rolls and the mandrel mechanism associated with the rolls, and that the term "billet" is used to designate any form of work piece, whether it be technically known as a billet, ingot or bloom.

The object of the invention, generally stated, is to so improve the construction of piercing mills and their constituent elements that the outputs of the mills may be greatly increased and that billets may be more accurately pierced by them.

A specific object is to provide means associated with a set of piercing rolls for so supporting a mandrel and a billet to be pierced that the mandrel will properly enter the center of the billet and thereby avoid or lessen the liability of eccentric piercing.

A further specific object is to provide an improved mandrel carriage for piercing mills to the end that billet-piercing and mandrel-stripping operations may be simultaneously conducted with consequent increase in the output of the mill.

A still further specific object is to improve the constructions of water-cooled mandrels and their supports.

The means for attaining these and other objects are explained in the following description of the invention with reference to its embodiment illustrated in the drawings, of which Fig. 1 is a plan view of a piercing mill; Fig. 2 a vertical sectional view taken on the broken lines II-II, Fig. 1; Fig. 3 a transverse sectional view of a stand of piercing mill rolls, the plane of view being indicated by the line III-III, Fig. 2; Fig. 4 a view to enlarged scale of the working pass shown in Fig. 3; Fig. 5 a vertical sectional view of a mandrel bar carriage, the plane of view being indicated by the line V-V, Fig. 1, with the exception that one of its mandrel bar supports and its attached mandrel bar is shown as extending vertically upward; Fig. 6 a plan view to enlarged scale of one of the mandrel bar supports, portions of gear housings being in section to show the construction of their contained gears; Fig. 7 a transverse sectional view of a mandrel bar

support taken on the line VII-VII, Fig. 6; Fig. 8 a longitudinal sectional view of a mandrel bar support and attached mandrel bar taken on the line VIII-VIII, Fig. 6; Fig. 9 a side view of a form of water-cooled mandrel bar and attached mandrel head; Fig. 10 a longitudinal central sectional view of the outer end of the mandrel bar and of the mandrel head shown in Fig. 9; and Fig. 11 a view corresponding to Fig. 10 showing a modification of construction in which the mandrel head as well as the mandrel bar is water-cooled.

According to this invention, there is associated with a set of piercing rolls a mandrel carriage provided with a plurality of mandrel bar supports, the carriage being movable transversely of the line of feed of a billet through the piercing rolls, and the mandrel bar supports being mounted for independent movements, preferably vertical, so that a billet may be pierced over a mandrel head on one mandrel bar while a pierced billet may be removed from another mandrel bar. Provision is made for properly cooling the mandrel bars and mandrel heads when desired, and for so supporting the rear end of a mandrel bar that during a piercing operation it is free to swing laterally in all directions in accordance with exigencies of the operation. Associated with the piercing rolls means are provided for supporting at the beginning of a piercing operation in proper relationship with each other and with the rolls the forward end of a mandrel and the end of a billet to be pierced so that the mandrel head will enter the center of the billet and thereby avoid eccentric piercing.

Having reference first to the general arrangement of the mill shown in the embodiment of the invention illustrated in the drawings, a mandrel carriage 1 is shown as being supported upon tracks, ways or slides 2 for movements transversely of the line of feed through a pair of piercing rolls 3 which are rotatably mounted in suitable roll housings 4. While the piercing rolls may be of any preferred form or type, they are shown as being in general of the Mannesmann type, but with curved faces, having their axes of rotation inclined to each other in the well known manner, and being adapted to be rotated by suitable driving connections (not shown) connected to the outer end of their necks.

The mandrel carriage is provided with a plurality of supports, preferably two, for mandrel bars 5 and 6, which supports are independently movable upon the carriage so that one bar may, as shown in Fig. 1, be arranged between the piercing rolls for a billet-piercing operation, and another be swung to a position for stripping a pierced billet from it. As seen in Fig. 3 the upper portions of 10 the roll housings are flared outwardly to permit the mandrel bars to be moved laterally while being placed in or taken from billet-piercing position. These housings are of rigid construction, bolted together as indicated to resist the thrusts of the rolls, and the rolls are mounted in the housings for lateral movements, both for adjustment and to spread the rolls in case cobbles are struck.

The detail construction of the mill will now 20 be explained, reference being first made to certain mandrel and billet supports associated with the piercing rolls, and thereafter to the mandrel carriage and its mandrel bar supports.

25 Considerable difficulty has been heretofore experienced in causing a piercing mandrel head to always enter the center of a billet to be pierced, and when a head does not enter the center of the billet, the billet becomes 30 pierced eccentrically throughout all or a portion of its length. To overcome this difficulty means are arranged between the piercing rolls for supporting at the beginning of a piercing operation and in proper relation to each other and to the rolls the forward end of a mandrel and the end of a billet to be pierced, it being understood that the term "mandrel" is herein used to designate the 35 mandrel bar and head as a unit. The preferred means for this purpose is a billet-supporting roller 10 (Figs. 2-4) and a mandrel supporting bracket 11. Roller 10 may take the form of a similar roller disclosed in my United States Patent No. 1,586,975, and may, 40 in addition to supporting the end of a billet in proper relation to a mandrel, also function as explained in that application. The roller is mounted on a horizontal axis, transverse to the axes of the piercing rolls, in vertically adjustable bearings 12 arranged at the 45 sides of the piercing pass so that scale will not fall upon the bearings.

50 Mandrel-supporting bracket 11 is preferably rotatably mounted to swing to and from its operative position, and to such end it may be provided with hubs 13 engaging the inner ends of the bearings of billet-supporting roller 10. Normally, the weight of bracket 11 tends to swing it to its lower inoperative position, although its weight is preferably counterbalanced in part by a weight 14 attached to the bracket on the opposite side of its axis of rotation. For moving the bracket 55 upwardly to its mandrel-supporting position indicated in Fig. 2, the bracket may have a

lug 15 provided with an adjusting screw 20, the lower end of which is adapted to be engaged by the upper end of a movable rod 16. This rod is provided at its lower end with a piston or head 17 arranged in a cylinder 18, 70 to and from which pressure fluid may be supplied and exhausted through a pipe 19.

At the beginning of a piercing operation pressure fluid is admitted to cylinder 18 to move rod 16 upwardly to raise bracket 11 to 75 its mandrel-supporting position. The position of adjusting screw 20 is such that, when piston 17 is at its uppermost position in cylinder 18, bracket 11 is in its required position for so supporting a mandrel that the point of 80 its head is in alignment with the axis of a billet 21 supported on roll 10. After the mandrel head has entered the center of a billet and the piercing operation has started, pressure fluid is exhausted either manually or 85 otherwise from cylinder 18 to permit bracket 11 to be moved downwardly out of the path of the pierced portion of a billet, it being understood that even although pressure fluid does not then act to hold bracket 11 upward- 90 ly, the bracket is not, because of the friction between it and the mandrel head, free to swing or move downwardly. It therefore requires the movement of the billet to move bracket 11 out of the path of the pierced portion of the billet. 95

Having reference now to mandrel carriage 1, it has already been explained that it is mounted upon tracks or ways 2 for movements transversely of the line of feed through 100 the piercing rolls. For effecting such movements, the lower portion of the carriage may be provided with lugs 25 (Fig. 5) between which there is arranged an internally threaded sleeve 26 which receives a threaded feed screw 27 adapted to be rotated by a reversible motor 28 suitably connected to the outer end of the screw. By operating motor 28 in one direction or the other the mandrel carriage is 105 moved to and fro upon its ways. 110

The inner ends of mandrel bars 5 and 6 are attached to supports 30 and 31, respectively. The construction and operation of each support is the same and each is provided with like independent means for rotating it 115 on a horizontal axis to swing its attached mandrel bar to and from piercing and stripping positions. The construction of mandrel support 31 will now be explained, it being understood that what is said concerning it applies likewise to support 30. 120

Support 31 is mounted for adjustment longitudinally in a housing 32 (Figs. 5, 6 and 8) provided with trunnions 33 and 34 rotatably mounted in brackets 35 and 36 supported by carriage 1. Trunnion 34 has keyed to it a gear 37 which meshes with a pinion 38 (Fig. 1) attached to a shaft 39, to which there is also attached a worm gear 40 (Fig. 2) meshing with a worm shaft 41 attached to the rotor 125 130

of a reversible motor 42. Through this train of driving connections the operation of motor 42 in one direction or the other causes mandrel support 31 to swing on its horizontal trunnions 33 and 34.

The preferred construction of each mandrel bar support is best seen to enlarged scale in Figs. 6, 7 and 8. Briefly, the support comprises means for adjusting it longitudinally in its housing to properly position the end of a mandrel between the piercing rolls, means for attaching a mandrel bar to the support so that the bar may rotate upon its longitudinal axis, and may also move laterally in any direction according to the exigencies of a piercing operation, and means for supplying water or other cooling fluid through the support and its attached mandrel bar.

For adjusting mandrel bar support 31 within its housing 32, and also for connecting the support to the housing to resist longitudinal thrusts and pulls upon its attached mandrel bar, support 31 is attached to housing 32 by means of a plurality of screws 45, each of which engages an internally threaded nut 46 secured in a lug 47 projecting laterally from and formed integrally with housing 32, the several nuts 46 being held in these lugs by means of a ring 48 attached to housing 32. The outer ends of screws 45 are provided with pinions 49 each of which meshes with an external worm wheel ring 50 rotatably mounted upon the forward end of support 31. Meshing with ring 50 there is a worm shaft 51 attached to a rod 52 adapted to be rotated by a hand wheel 53. The rotation of worm shaft 51 by hand wheel 53 causes ring 50 to rotate upon support 31, and such rotation of this ring rotates pinions 49 to cause screws 45 to move inwardly or outwardly of lugs 47 to move support 31 with relation to housing 32.

Within housing 32 there is a water-cooled thrust bearing sleeve 55 provided with a series of inwardly extending rings 56, between which there are disposed rings 57 projecting outwardly from a central thrust block or hub 58. Between rings 56 and 57, there is an extended layer of bearing metal 59 so that block 58 may rotate within thrust bearing 55 in response to the rotation of a mandrel bar during a piercing operation. Bearing 55 is formed of two or more parts laterally applicable to block 58 when the latter is removed from support 31, and this bearing is held at its ends in its indicated position by a ring 60 bolted to support 31 and by an in-turned flange 62 forming a part of support 31.

The forward end of block 58 is provided with a spherical bearing 65 for receiving a spherical head 66 forming part of a mandrel coupling member 67 which projects forwardly of block 58 and lies in the forward end of support 31. The outer end of coupler 67 is provided with a socket 68 for receiving

the inner end of mandrel bar 6, which bar is attached to the coupler by means of a ring 69, through which bolts 70 extend and engage the coupler, such bolts also passing through collars 71 projecting outwardly from the inner end of mandrel bar 6 to cause the coupler to rotate with the bar.

The outer end of coupler 67 is provided with a flange 75 for receiving a bearing ring 76 the outer face of which bears against a ring 77 attached by bolts 78 to support 31. So that the outer end of coupler 67 may move laterally in any direction which it may be caused to move by a piercing operation, the outer bearing face of ring 76 is of spherical form, the radius of curvature of which is struck from the center of spherical head 66 at the inner end of the coupler. While these lateral movements of the mandrel bar are made effective from the center of spherical head 66 of coupler 67, axial rotation of the mandrel bar is transmitted from coupler 67 to block 58 by means of lugs 79 which project laterally from coupler 67 and are arranged between lugs 80 projecting forwardly from blocks 58, there being sufficient space between these interengaging lugs 79 and 80 to permit of such lateral movement as may be imparted to the coupler by a piercing operation. At the outer end of the coupler provision is made by a space 81 between the inner face of ring 77 and the outer face of bearing 76 to permit lateral movement of the outer end of the coupler, and for the same purpose there is an annular space 82 between an inturned flange 83 of ring 69 and an outwardly turned flange 84 of ring 77, such overlapping flanges being provided for excluding scale, grit, etc. from the bearing formed between rings 76 and 77.

As far as concerns some features of the invention the mandrel bar need not be cooled, or if cooled water or other cooling fluid may be led to and from it in various ways. However, when the mandrel bar is cooled, cooling fluid is preferably led to its interior through passageways formed in bearing block 58 and coupler 67, the water being caused to first flow through the annular cooling chamber formed in bearing sleeve 55. For this purpose a water distributing casing 85 may be attached to the rear of mandrel support and be connected by a sliding packing gland to a water supply pipe 86. Water from pipe 86 flows through a port 87 of casing 85 into water chamber 88 of sleeve 55, from which it flows through a casing port 89 into a central bore 90 of block 58 which is provided with a tubular extension rotatably mounted in a packing gland attached to casing 85. Supply pipe 86 is connected to housing 32 and communicates with a passageway 91 formed in the housing, which passageway in turn communicates at its inner end with the inner end of passageway 92 formed in trunnion 130

34, the outer end of passageway 92 being connected to a stand pipe 93 (Figs. 1 and 5).

Water flowing from casing 85 into bore 90 of block 58 enters the inner end of coupler 67 and flows from such coupler through a tube 95 arranged centrally within mandrel bar 6. This tube extends to the outer end of the mandrel bar and forms with it an annular outlet passage for rearward flow of water. 10 From this annular passageway water flows through ports 96 at the inner end of mandrel bar 6, ports 97 at the outer end of coupler 67 and ports 98 in mandrel bar support 31.

Having reference now to Figs. 9 and 10, the outer end of mandrel bar 6 is shown as having attached to it a holder 100 provided with a mandrel head 101. This holder preferably has a sleeve 102 provided with an external tapered thread adapted to receive an internal thread formed at the outer end of mandrel bar 6, the holder being provided exteriorly with holes or sockets 106 for engagement by a bar or spanning wrench for connecting the holder to or disconnecting it from the bar. Spanner wrench holes 106 are located at a position on the mandrel head where the pierced portion of a billet clears the surface of the head. The inner end of sleeve 102 is provided internally with a series of projections 103 for receiving the outer end of tube 95, the ends of these projections being chamfered as indicated so that when the mandrel holder is applied to the mandrel bar the outer contracted end of tube 95 may be easily positioned at the center of sleeve 102 and concentrically within the mandrel bar. Cooling water flowing longitudinally within tube 95, passes around its end, and then flows outwardly through the spaces formed between projections 103 and the outer face of the tube as indicated by arrows 105. The water then flows rearwardly on the outside of the tube 95, and escapes at the inner end of the mandrel bar through the several ports explained above. To the end that the cooling water may effect a maximum absorption of heat from the mandrel bar, tube 95 is of such size that there is a relatively small space between its exterior and the interior of the bar. In this way a rapid rearward flow of water is effected adjacent to the mandrel bar with a correspondingly large heat absorption.

In using mandrel heads such as shown in Fig. 10 they become so heated during a piercing operation that it is generally necessary to replace them between piercing operations. The piercing mill herein disclosed is especially well adapted for this because the heads may be changed in the interim between piercings on the respective mandrels. However, one feature of this invention has to do with the provision of a water-cooled mandrel which need not be removed, the pre-

ferred construction being that illustrated in Fig. 11. As there shown, a mandrel 110 is provided with a central cavity 111, and central tube 112 of mandrel bar 6 is provided with an extension tube 114 projecting substantially to the end of this cavity. The inner end of extension tube 114 is engaged exteriorly by a ring 115 which fits fairly loosely within tube 112, and which is provided exteriorly with an expansible packing ring 116. The inner end of mandrel 110 is provided exteriorly with a tapered thread to engage an internal tapered thread formed at the end of mandrel bar 6, and is provided with a sleeve 117 having projections 118 formed on its outer face to support the outer end of tube 112 and at the same time permit the outward flow of water into the annular passageway between tube 112 and mandrel bar 6. Water from the interior of tube 112 flows in the path indicated by the arrows 80 through extension tube 114, around its outer end, then rearwardly between tube 114 and the inner face of the mandrel, then between projections 118 to the outside of tube 112 which forms with the interior of bar 6 a small space for effecting rapid rearward flow of water for the purpose already explained.

In the operation of the mill, assuming as a starting point that its parts are in the positions generally indicated in Fig. 1, a billet 21 is placed with its entering end upon billet supporting roller 10, the outer end of mandrel 5 being supported by bracket 11 held in its upper position by admitting pressure fluid to cylinder 18 to raise rod 16, and the inner end of the mandrel bar being supported by the spherical head 66 of coupler 67. Roller 10 and bracket 11 thus position billet 21 and mandrel 5 in such position with relation to each other and to the pass between the piercing rolls, that the end of the mandrel head will enter the center of the billet. The center line of the pass or billet is preferably below the narrowest space between the main rolls thus thrusting the billet against its supporting roll 10. As the piercing rolls are rotated and the piercing operation progresses, pressure fluid is exhausted from cylinder 18 to permit bracket 11 to move downwardly out of the path of the pierced portion of the billet. During the piercing operation, water is caused to flow through mandrel bar 5, and also through the mandrel head in case mandrel head 110 of Fig. 11 is attached to the end of the bar. The line of flow of cooling water is from casing 85 through passageway 90 in block 58, and then through coupler 67 and mandrel bar tube 95 to the outer end of the mandrel bar. It then flows rearwardly on the outside of tube 95 and escapes through ports 96, 97 and 98. As the rear end of the billet passes over the mandrel head the collars shown at the ends of the

piercing roll continue to rotate and feed the pierced billet over the mandrel bar until the pierced billet is moved entirely beyond the roll.

- 5 At the end of the piercing operation, motor 42 is set in operation for swinging the mandrel upwardly with the pierced billet surrounding the mandrel bar, and when this mandrel is clear of the piercing rolls and 10 their housing, motor 28 (Fig. 5) is operated to move carriage 1 transversely to bring mandrel bar 6 in a position to be lowered between the piercing rolls. While the mandrels are so moved each is supported at its 15 inner end by the spherical head 65 on coupler 67 and by flange 84 of ring 69 which then rests upon flange 83 of ring 77 (Fig. 8). Continued operation of motor 42 for raising mandrel 5 causes such mandrel to swing 20 to the opposite side of the mandrel carriage in a position for stripping the pierced billet from it by suitable mechanism provided for this purpose and which is not shown. While the stripping of the billet from mandrel 5 25 is in progress, the piercing of another billet upon the mandrel head at the end of mandrel bar 6 simultaneously takes place. This operation is repeated at the completion of the piercing of each billet, carriage 1 being 30 alternately moved backwardly and forwardly transversely of the line of feed through the piercing rolls, and motors 42 being operated to swing the mandrels alternately to and from billet-piercing and mandrel-stripping 35 positions. By the use of this mechanism, the piercing rolls may be operated substantially continuously so that an adequate supply of pierced billets may be supplied to a tube forming mill.
- 40 For adjusting each mandrel bar support in its housing to properly position the end of its attached mandrel head for a piercing operation, hand wheel 53 (Fig. 7) is turned to rotate screws 45. It will be understood, 45 however, that such adjustment is not required for each piercing operation, but usually only when adjusting the mill for forming different sized pierced billets. The rotation of the mandrel bar consequent upon the action of 50 the piercing rolls is transmitted through mandrel bar coupler 67 to block 58 which is rotatably mounted within water-cooled sleeve 55. The lateral movement of the outer end of the mandrel during the piercing operation 55 is made effective from the center of spherical head 66 at the inner end of coupler 67 so that no strain is placed upon the mandrel bar or upon the coupler.

According to the provisions of the patent 60 statutes, I have explained the principle and operation of my invention and have illustrated and described what I now consider to represent its best embodiment. However, I desire to have it understood that, within the 65 scope of the appended claims, the invention

may be practiced by other forms of mills and by mills embodying other details of construction than particularly shown and described.

I claim as my invention:

1. In a billet-piercing mill, the combination with a set of piercing rolls, of a plurality of mandrel supports associated with said rolls and each independently movable alternately in opposite directions to and from piercing and stripping positions whereby piercing and stripping operations may be simultaneously conducted. 70
2. In a billet-piercing mill, the combination with a set of piercing rolls, of a mandrel carriage movable transversely of the line of feed of a billet between said rolls, and a plurality of mandrels supported by said carriage for independent movements, whereby one mandrel may be moved to and held in piercing position while another mandrel may be 75 moved from piercing to stripping position. 80
3. In a billet-piercing mill, the combination with a set of piercing rolls, of a mandrel carriage movable transversely of the line of feed of a billet between said rolls, a plurality of mandrel bars provided at their outer ends with mandrel heads and having their inner ends supported by said carriage for independent vertical swinging movements, whereby one mandrel may be moved to and held in 85 piercing position while another mandrel may be moved from piercing to stripping position. 90
4. In a billet-piercing mill, the combination with a set of piercing rolls, of a mandrel carriage movable transversely of the line of feed of a billet between said rolls, a pair of mandrel bars provided at their outer ends with mandrel heads and having their inner ends supported by said carriage for vertical 95 swinging movements, means for effecting said transverse movements of the carriage, and separately operable means for swinging said mandrel bars whereby one mandrel may be moved to and held in piercing position simultaneously with the movement of another mandrel from piercing to stripping position. 100
5. In a billet-piercing mill, the combination with a set of piercing rolls, of a mandrel carriage movable transversely of the line of feed of a billet between said rolls, a plurality of mandrel supports each mounted on said carriage on an axis for independent vertical swinging movements, motors borne by said carriage, and driving connections 115 from each motor to each mandrel support 120 for swinging it. 125
6. In a billet-piercing mill, the combination with a set of piercing rolls, of a mandrel bar support housing, a mandrel bar support mounted in said housing for longitudinal adjustment with relation to it, a plurality of screws connecting said support with said housing, and means for simultaneously rotating said screws to move the support with relation to the housing. 130

7. In a billet-piercing mill, the combination with a set of piercing rolls, of a mandrel bar support housing rotatably mounted on a horizontal axis for vertical swinging movement, a mandrel bar support mounted in said housing for longitudinal adjustment with relation to it, a plurality of screws connecting said support with said housing, and means for simultaneously rotating said screws to move the support with relation to the housing.

8. In a billet-piercing mill, the combination with a set of piercing rolls, of a mandrel bar support housing rotatably mounted on a horizontal axis for vertical swinging movements, a mandrel bar support mounted in said housing for longitudinal adjustment with relation to it, a mandrel coupler having at its inner end a universal joint connection to said support, a mandrel bar, and means for rigidly attaching the rear end of said bar to the outer end of said coupler.

9. In a billet-piercing mill, the combination with a set of piercing rolls, of a mandrel bar support housing rotatably mounted on a horizontal axis for vertical swinging movements, a mandrel bar support mounted in said housing for longitudinal adjustment with relation to it, means for effecting said longitudinal adjustment, a coupler having at its inner end a universal joint connection with said support, a mandrel bar, and means for rigidly attaching the rear end of said bar to the outer end of said coupler, the outer end of said support being provided with means for engaging the outer end of said coupler permitting lateral movement of the outer end of the coupler in all directions.

10. In a billet-piercing mill, the combination with a set of piercing rolls, of a mandrel bar support housing rotatably mounted on a horizontal axis for vertical swinging movements, a mandrel bar support mounted for longitudinal adjustment in said housing, a mandrel coupler pivotally connected at its inner end to said housing for universal lateral movements of the outer end of the coupler with relation to the housing, a tubular mandrel bar rigidly connected to the outer end of said support, and cooling fluid passageways extending through said housing support and coupler for introducing cooling fluid into said mandrel bar.

11. In a billet-piercing mill, the combination with a set of piercing rolls, a mandrel comprising a bar provided at its forward end with a mandrel head, and means for supporting the rear end of said bar; of means for supporting the forward end of said mandrel at the beginning of a piercing operation in proper position for said mandrel head to enter the end of a billet to be pierced, said last-named mandrel supporting means being movable by the movement of a billet being pierced out of the path of its pierced portion.

12. In a billet-piercing mill, the combination with a set of piercing rolls, a mandrel comprising a bar provided at its forward end with a mandrel head, and means for supporting the rear end of said bar; of means for supporting in the piercing pass of said rolls the entering end of a billet to be pierced, and means for supporting at the beginning of a piercing operation the forward end of said mandrel in a position for entering the center of an end of a billet to be pierced, said last-named mandrel supporting means being movable by the movement of a billet being pierced out of the path of its pierced portion.

13. In a billet-piercing mill, the combination with a set of piercing rolls, a mandrel comprising a bar provided at its forward end with a mandrel head, and means for supporting the rear end of said bar, of a roller mounted on a horizontal axis transverse to the line of feed through said rolls and arranged below the piercing pass of said rolls for supporting the forward end of a billet to be pierced, and means for supporting at the beginning of a piercing operation the forward end of said mandrel in a position for entering the center of an end of a billet to be pierced, said last-named mandrel supporting means being movable by the movement of a billet being pierced out of the path of its pierced portion.

14. In a billet-piercing mill, the combination with a set of piercing rolls, a mandrel comprising a bar provided at its forward end with a mandrel head, and means for supporting the rear end of said bar; of means for supporting the forward end of a billet to be pierced, and a bracket movable to a position for supporting at the beginning of a piercing operation the forward end of said mandrel at the center of the entering end of a billet to be pierced, said bracket being subsequently movable by the movement of a billet being pierced from said position out of the path of the pierced portion of the billet.

15. In a billet-piercing mill, the combination with a set of piercing rolls, a mandrel comprising a bar provided at its forward end with a mandrel head, and means for supporting the rear end of said bar; of means for supporting the forward end of a billet to be pierced, a vertically movable bracket for supporting at the beginning of a piercing operation the forward end of said mandrel in position for entering the center of the end of a billet to be pierced, and releasable means for holding said bracket in said position.

16. In a billet-piercing mill, the combination with a set of piercing rolls, a mandrel comprising a bar provided at its forward end with a mandrel head, and means for supporting the rear end of said bar; of means for supporting the forward end of a billet

- to be pierced, a bracket rotatably mounted on a horizontal axis for supporting at the beginning of a piercing operation the forward end of said mandrel in position for 5 entering the center of the end of a billet to be pierced, and power-actuated mechanism for moving and holding said bracket in said position.
17. In a billet-piercing mill, the combination 10 with a set of piercing rolls, a mandrel comprising a bar provided at its forward end with a mandrel head, and means for supporting the rear end of said bar; of a roller rotatably mounted on a horizontal axis trans- 15 verse to the line of feed through said rolls and arranged below said rolls for supporting the forward end of a billet to be pierced, a bracket rotatably mounted on the axis of said roller for supporting at the beginning 20 of a piercing operation the forward end of said mandrel in a position for entering the center of a billet to be pierced, and power-
- actuated mechanism for moving and holding said bracket in said position.
18. In a piercing mill, the combination 25 with a set of piercing rolls, and a mandrel support; of a tubular mandrel bar attached at its rear end to said support, a mandrel head provided with a concavity detachably connected to the outer end of said bar, a 30 tube extending concentrically through said mandrel bar from its rear to its forward end, and a second tube telescoping with and ex- tending from the forward end of said first- 35 mentioned tube into the concavity of said mandrel head, said tubes forming a passage- way for the circulation of fluid through their interior and between their exterior surface and the interior walls of the mandrel bar and mandrel head, for cooling the mandrel bar 40 and head.

In testimony whereof, I sign my name.

SAMUEL E. DIESCHER.
